UNITED STATES PATENT OFFICE.

FREDERICK W. VON OVEN, OF AURORA, ILLINOIS.

FILTER-PRESS.

No. 872,008.

Specification of Letters Patent.

Patented Nov. 26, 1907.

Application filed April 26, 1907. Serial No. 370,490.

To all whom it may concern:

Be it known that I, FREDERICK W. VON OVEN, a citizen of the United States, residing at Aurora, in the county of Kane and State of Illinois, have invented a new and useful Improvement in Filter-Presses, of which the following is a specification.

The object of my invention is to provide a novel construction, in matters of detail, of filter-press to the ends of increasing the efficiency of the press and reducing the liability to fracture of the filtering-frames under the pressure to which they are subjected in use, and to the further end of avoiding all necessity of cutting holes in the filter-cloths for allowing the feed-inlets to extend through the series of filter-plates into the respective filter-chambers.

Referring to the accompanying drawings—
Figure 1 is a view in side elevation of a filter-press embodying my improvements; Fig. 2, a section taken at the line 2 on Fig. 1, viewed in the direction of the arrow and enlarged, with parts of the cell-structure broken away to disclose details; Fig. 3, a broken section through the feed-passage, taken at the line 3 on Fig. 2, viewed in the direction of the arrow and enlarged; Fig. 4, a broken section through the re-wash passage, taken at the line 4 on Fig. 2, viewed in the direction of the arrow and enlarged; Fig. 5, a section taken at the line 5 on Fig. 6 and viewed in the direction of the arrow, showing the construction of the packing between joints of the feed-passage; Fig. 6, a section taken at the line 6 on Fig. 5 and viewed in the direction of the arrow, showing the feed-port-containing rubber-gasket employed between frame-joints in the feed-passage; Fig. 7, a section taken at the line 7 on Fig. 5 and viewed in the direction of the arrow, showing the manner of yieldingly fastening the aforesaid gasket in place, and Fig. 8, a broken section showing the same, taken at the line 8 on Fig. 5 and viewed in the direction of the arrow.

The supporting frame-work of the press, which is bolted to a base 9, (as a floor) consists of an end-frame 10, preferably a casting, and an end-frame 11, also preferably a casting, having integrally formed with it the stationary head 12 of the press. The movable parts of the press, hereinafter described, are confined between and reciprocably supported upon side-bars 13 extending between and bolted to the sides of the frames 10 and 11. The movable head 14 is supported at rollers 15 project-

ing from its sides on the bars 13, and also at flanges 16 projecting from its sides to bear against the tops of the supporting bars, this head being centrally engaged by a screw 17 working in a bearing in the frame 10 and carrying on its outer end a hand-wheel 18.

The parts thus far described are common in filter-presses of the type to which my invention relates, the features of novelty being contained in the chamber-forming frames interposed between the heads 12 and 14, all of which are constructed substantially alike, so that the following description of one will apply to each: The frame-rim 19 is a metal casting preferably of rectangular form, with its inner edges beveled and having a central flange 20 extending about them to afford on its opposite sides shoulders 21. Screens 22 and 23, of perforated or woven metal, fit in each frame, abutting against the opposite shoulders 21, to which they may be fastened at intervals. Interposed between each pair of screens, and fitting the interior of the rim more or less loosely, is an open-work mat 24, preferably of woven wire with a coarse mesh. A sheet 25 of filtering cloth is folded to hang over the upper edge of the frame and cover the faces of its two contained screens; and near its lower corner the frame-rim contains an outlet-port 26 provided with a draw-off faucet 27. On the horizontally opposite corner-portion of the rim is cast an ear 28 provided with a transverse opening 29 and containing in one side a curved recess 30, in which is confined a strip of packing 31, of rubber or other suitable material, of the preferred cross-sectional shape represented in Fig. 3, this packing-strip projecting beyond this surface of the ear and frame-rim. In each side of the frame-rim adjacent to the ear thereon is provided an upright recess 32, of the shape illustrated in Fig. 6, involving a vertical back and similar oblique ends, in which fits one side of a gasket 33, of rubber or other suitable material, of the general lozenge-shape represented to cause it to conform to and fit the recess 32, and containing an elongated opening 34, which is lined with a metal thimble 35 forming an inlet-port. Metal sockets 36, 36 project from the thimble beyond the outer edge of the gasket to confine the heads of screws 37 extending through the bases of the sockets into the side of the frame and afford to the gasket slight movement longitudinally of the screw-shanks and thus lengthwise of the

press. In applying the filtering cloth, as hereinbefore mentioned, the edge thereof requires to enter between the gasket 33 and the adjacent recess 32, and the slight movement thus afforded to the gasket permits such introduction of the adjacent portion of the edge of the sheet. From the upper end-portion of the side of the frame-rim 19 provided with the ear 28, there projects an ear 10 38 containing a tubular opening 39 for the re-wash purpose of the press, and a port 40 leads from this passage to the interior of the frame. On each side of the frame-rim is a handle 41 by which to slide it on its bearings 16 upon the side-bars 13.

To form the press illustrated in Fig. 1, frames are assembled to be supported at their flanges 16 between the bars 13 to adapt them to slide thereon and abut flatwise one 20 against the other, with gaskets 42 (Fig. 4) interposed between the ears 38 and let into recesses in the head 14 and alternate frame-rims. Before compressing the frames together, each has hung upon it its filtering 25 cloth 25, the edges of which overlap the inner beveled rim-edges, to be clamped between frames in pressing them together by turning the screw 17 to advance the head 14 on its bearings and force the frames ahead of it 30 against the stationary head 12. With the parts thus assembled, the openings 29 aline to form the feed-passage to the machine for the material to be filtered, and the openings 39 aline to form the inlet passage for the hot 35 water used for the re-washing purpose, the supply of material to be filtered entering the passage 29 through a valve-controlled pipe 43 on the head 12, the filtrate discharging through the faucets 27; and a valved pipe 44, 40 for supplying the re-wash water, leads to the passage 39 at one end thereof. With the frames thus assembled and pressed together, their opposing rim-sides meet with water-tight junction, which is assisted by the inter- 45 posed cloth clamped between them and by the packing 42; while the packing strips 31 and gaskets 32 effectually seal the joints between the ears 28, the openings in which 50 form the feed-passage 29, with a port 34 in each gasket leading centrally into the base of each filtering chamber formed by a pair of the frames and by the end frames with the heads, the width of the chamber being such as may be desired according to the trans- 55 verse width of the rims. Thus each frame, including its perforated center-portion, constitutes a chamber-forming element.

In the use of the press, the material to be filtered, fed along the passage 29, enters 60 through the different ports 34 into the respective chambers, from each of which the liquid passes through the cloth forming its opposite walls, and the filtrate discharges through the faucets 27. When the chambers 65 become filled with cakes of the solid matter

retained in them from the material undergoing filtration, alternate faucets 27 are closed, leaving the others open, and hot water or other liquid for the re-wash is introduced by way of the passage 39 and ports 70 40 into alternate chambers, for the usual purpose of taking up filtrate left in them. The ports 40 are only provided for alternate filtering chambers, namely those of which the faucets are closed, and they lead through 75 the rims directly between the screens of the respective frames, so that the re-wash water may pass through the filtering-cloths in the direction, opposite that of the passage 80 through them of the filtrate.

It will be observed that the construction of the frames, with the screens and interposed mats filling their rims, and the purpose of which is to afford backing for the filtering cloth, renders the interior of the press 85 practically one continuous filtering-chamber containing at intervals cloth-covered open-work partitions of a character so flexible as to adapt them to yield rather than break under excessive pressure. In the event, however, of the perforate center-portion forming the wall in any frame, being forced out of place by excessive pressure in the machine, the resultant damage to the press is comparatively slight and may easily be repaired. 90

The space formed by the open-work matting permits the introduction between the filtering cloths of a solid sheet of liquid. The open-work screens supporting filtering surfaces may be employed in the "recessed-frame" type of filter-press and also in the "mud-ring" type wherein the mud-ring determines the thickness of the cake or filtering mass. Moreover, the screens between filtering cloths give perfect freedom to the passage of the filtered liquid to the outlet-cocks directly from all parts of the filter-chambers after passing through the filter-cloths; that is to say, the liquid is not required to follow any defined channel, which may be over-crowded or choked, and thus tend to obstruct or retard the discharge. 105

The described construction not only avoids all necessity of cutting holes in the filtering-cloths, but enables the use to be dispensed with of clips, and the like, for fastening such openings tightly about port-openings, and which tend to reduce the area of filtering surface; and besides the cake which forms about such openings tends to softness, while the present construction produces uniform density throughout the cake. 115

What I claim as new and desire to secure by Letters Patent is—

1. In a filter-press, the filter frames having inlet-ports in the junctions between them and provided with ears containing openings forming a feed-passage common to said ports. 125
2. In a filter-press, a chamber-forming ele- 130

- ment consisting of a frame comprising a rim and an open-work flexible center-portion within it, with filtering-cloth covering the frame-sides.
- 5 3. In a filter-press, a chamber-forming element consisting of a frame comprising a rim, screens with an interposed open-work mat confined within the rim, and filtering-cloth covering the frame-sides.
- 10 4. In a filter-press, a chamber-forming element consisting of a frame comprising a rim having inwardly beveled edges and a flange affording shoulders extending about its inner edges, screens abutting against said shoulders, and an open-work flexible mat interposed between the screens, and filtering-cloth covering the frame-sides.
- 15 5. In a filter-press, the combination with a stationary head and a movable head, of interposed chamber-forming frames comprising rims with open-work flexible center-portions, ears projecting from said rims and containing openings alining in the press to form the feed-passage thereto, ports leading from said passage into the chambers between frames, and filtering-cloth covering the frame-sides.
- 20 6. In a filter-press, the combination with a stationary head and a movable head, of interposed chamber-forming frames comprising rims with open-work flexible center-portions, ears projecting from said rims at one side of the press and containing openings alining in the press to form the feed-passage thereto, ports leading from said passage into the chambers between frames, filtering-cloth covering the frame-sides, ears projecting from said rims at said side and containing openings alining in the press to form the re-wash passage thereto, with ports leading
- 25 from said re-wash passage to the chambers, and draw-off faucets on the rims at the opposite side of the press and communicating with said chambers.
- 30 7. In a filter-press, the combination with a stationary head and a movable head, of interposed chamber-forming frames comprising rims with open-work flexible center-portions, ears projecting from said rims at one side of the press and containing openings alining in the press to form the feed-passage thereto, ports leading from said passage into the chambers between frames, filtering-cloth covering the frame-sides, ears projecting from said rims at said side and containing
- 35 openings alining in the press to form the re-wash passage thereto, with ports leading from said re-wash passage through the rims of alternate frames to different chambers, and draw-off faucets on the rims at the oppo-
- site side of the press and communicating with said chambers.
8. In a filter-press, the combination with a stationary head and a movable head, of interposed cloth-covered chamber-forming frames, ears projecting from said frames at one side of the press and containing openings alining in the press to form the feed-passage thereto, and gaskets confined between said frames and containing metal-lined port-forming openings leading to said chambers.
- 15 9. In a filter-press, the combination with a stationary head and a movable head, of interposed cloth-covered chamber-forming frames, ears projecting from said frames at one side of the press and containing openings alining in the press to form the feed-passage thereto, and gaskets movably fastened to the frames and containing metal-lined port-forming openings leading to said chambers.
- 20 10. In a filter-press, the combination with a stationary head and a movable head, of interposed cloth-covered chamber-forming frames, ears projecting from said frames at one side of the press and containing openings alining in the press to form the feed-passage thereto, outer packing-strips confined between the ears, and inner gaskets confined between said frames and containing port-forming openings leading to said chamber.
- 25 11. In a filter-press, the combination with a stationary head and a movable head, of interposed cloth-covered chamber-forming frames, ears projecting from said frames at one side of the press and containing openings alining in the press to form the feed-passage thereto, similar recesses in the opposing sides of the frames, and gaskets containing ports leading to said chambers and shaped to conform to and fit said recesses.
- 30 12. In a filter-press, the combination with a stationary head and a movable head, of interposed cloth-covered chamber-forming frames, ears projecting from said frames at one side of the press to form the feed-passage thereto, similar recesses in the opposing sides of the frames, gaskets containing openings and shaped to conform to and fit said recesses, metal thimbles in the gasket-openings forming ports leading to the said chambers and provided with sockets, and screws confined at their heads in said sockets and fastened in said ears to permit movement on them of the gaskets.

FREDERICK W. VON OVEN.
